UNITED STATES PATENT OFFICE.

JAMES H. HAGAN, OF GLOVERSVILLE, NEW YORK.

SEWING-MACHINE.

1,087,489.

Specification of Letters Patent.

Patented Feb. 17, 1914.

Application filed March 5, 1913. Serial No. 752,157.

To all whom it may concern:

Be it known that I, JAMES H. HAGAN, a citizen of the United States, residing at Gloversville, in the county of Fulton and 5 State of New York, have invented certain new and useful Improvements in Sewing-Machines, of which the following is a specification, reference being had to the accompanying drawings.

10 This invention relates to improvements in sewing machines and more particularly to machines of that type employed in producing the diverging lines of ornamental stitching such as are commonly provided 15 upon glove-backs and similar articles.

The present invention has for its primary object the provision of simple and effective mechanism whereby the two outer lines of stitching will have the same degree of divergence with relation to the central line of stitching, and which will also insure an equal length of the lines or rows of stitching, produced upon each operation of the machine.

25 Another and more specific object of the invention is to provide in a machine of the above character tapering bars having spurred or roughened edges by which the material is held, as it is fed through the machine, and improved means for mounting said bars, whereby they may be easily and quickly interchanged and others substituted therefor, as the size of the glove or the particular circumstances may require.

30 Another object of the invention is to provide in a sewing machine of the type referred to, improved mechanism whereby the work may be accurately and expeditiously performed said mechanism being capable of 35 manufacture at comparatively small cost and adaptable to such machines now in common use without necessitating any material alterations in their construction.

With the above and other objects in view 40 as will become apparent as the description proceeds, the invention consists in certain constructions, combinations and arrangements of the parts that I shall hereinafter fully describe and claim.

45 For a full understanding of the invention, reference is to be had to the following description and accompanying drawings, in which—

Figure 1 is a side elevation of a sewing 50 machine illustrating the preferred embodiment of the present invention; Fig. 2 is a

plan view of the bed upon which the material is fed beneath the presser foot illustrating the mounting of the tapering blades. Fig. 3 is a longitudinal section taken on the 60 line 3—3 of Fig. 2; Fig. 4 is a transverse section taken on the line 4—4 of Fig. 1; Fig. 5 is an enlarged fragmentary elevation showing the position of the thread pulling fingers with the threads in position to be 65 cut; Fig. 6 is a detail perspective view of one of the diverging blades. Fig. 7 is a plan view of the presser foot; and Fig. 8 is a detail perspective view of the finger bar.

Referring in detail to the drawings, 5 designates the bed plate of a sewing machine, said machine being provided with the usual head 6 in which the vertically reciprocating needle bar 7 operates, any ordinary or approved mechanism being provided for the 70 actuation of said needle bar.

Upon the bed plate 5, the spaced parallel guide bars 8 are transversely arranged and provided with attaching flanges 9 whereby they may be bolted or otherwise rigidly secured upon the bed plate. The sewing machine is also provided with the usual presser foot 10 which is fixed upon the lower end of a vertically movable rod 11 mounted in the head 6. This presser foot is adapted to 80 be raised and lowered and when in its lowered position is disposed between the opposed edges of the guide bars 8. The presser foot 10 is provided in its body portion with spaced parallel slots 12, for a purpose which 85 will more fully appear from the following description.

Between the guide bars 8, the sliding cross heads 13 are mounted, the ends of said heads being notched as indicated at 14 to 95 receive the opposed edges of the bars 8. Upon these sliding cross heads 13 the longitudinally disposed blades 15 are mounted. These blades, as shown in detail in Fig. 6, gradually taper from one of their ends to 100 the other, and are provided at their narrow ends with the longitudinal extensions 16 which terminate in the notched lugs 17. The notches 18 in these lugs receive the upper edge of one of the sliding cross heads 13. 105 The blades 15 at their wider ends are also provided in their upper edges with notches 19 to receive the lower edges of their cross heads 13. The guide bars 8 are connected at their opposite ends by means of the stop plates 20 which limit the longitudinal movement of the heads 13 and the blades 15 car-

110

ried thereby. It will be noted from reference to Fig. 3 that the lower edges of the blades 15 are disposed in parallel relation to the guide bars 8 while their upper edges are 5 longitudinally inclined. These inclined edges of the blades are provided with short teeth or spurs 21 for gripping engagement with the material. The upper edges of the blades may be knurled or otherwise roughened for engagement with finer materials.

10 Upon the stop plates 20 at the forward ends of the guide bars 8, a longitudinally disposed finger or presser bar 22 is pivotally mounted as indicated at 23. This presser bar tapers longitudinally and extends toward the presser foot, said bar being located directly above and between the spaced 15 blades 15. This bar is normally held in an elevated position by means of a leaf spring 24 one end of which is fixed to the plate 20, the other end of said spring bearing against 20 the lower edge of the finger 22. The finger 22 is further provided with a depending pin 25 the function of which will be later referred to.

25 The body of the presser foot 10 is provided adjacent the outer edges of the slots 12 and between said slots with the needle receiving openings 26 through which the 30 needles 27 secured in any preferred manner in the needle bar 7 are extended in the downward stroke of the needle bar. The side walls of the slots 12 in the presser foot are preferably beveled or inclined in opposite directions as clearly shown in Fig. 35 4, so that they will exert a downward pull upon the material as it is fed through said slots by the blades 15.

35 As thus far described, the operation of the 40 invention is as follows: After the material has been properly cut, the central finger extensions are disposed upon opposite sides of the pin 25 on the finger bar 22 and said pin engaged with the crotch at the inner 45 ends of said finger extensions. The presser foot 10 being elevated, the material is passed under the same and engaged with the upper spurred edges of the blades 15. As the 50 machine is operated, the heads 13 are moved longitudinally upon the guide bars 8, the 55 upwardly inclined edges of the blades 15 passing through the slots 12 in the presser foot. As the wider ends of these blades move through the slots 12, the material is of course drawn upwardly through the presser 60 foot, thereby pulling upon the same and causing the rows of stitches formed by the needles 27 to diverge, said stitching lines or rows of course, being comparatively close 65 together at the start of the operation, and the two outer rows gradually diverging from the central row to a point adjacent the finger extensions, at the completion of the operation. By simply exerting a downward 70 pressure upon the finger bar 22, the mate-

rial is stretched into proper form over the upper edges of the blades 15 and is held in such form by the presser foot during the stitching operation. The finger bar 22 is forced downwardly by the operator until its lower end is in parallelism with the bed plate of the machine. Pressure upon this bar is then released so that the same will immediately return to its normal position.

70 In addition to the foregoing, I have devised improved means whereby the threads may be easily and quickly cut at the completion of each stitching operation. To this end, I secure to the upper end of the foot block, the bearing members 28 in which a transversely disposed shaft 29 is mounted. One end of this shaft is provided with a knurled head 30 whereby the same may be readily rotated or oscillated in its bearings. Upon this shaft, a plurality of arms 80 31 are fixed at one of their ends, said arms corresponding in number to the number of sewing needles. Upon one side of each of the arms 31, a bar 33 is secured by means of the screws 34. These bars project beyond the ends of the arms and are provided in their extremities with notches, which, in the normal positions of said bars are disposed in juxtaposition to the eyes of the respective needles. Upon the opposite end 85 of the shaft 29, a suitable weight 36 is secured which is disposed upon one side of the axis of the shaft and normally holds the bars 33 in the position shown in Fig. 1. When it is desired to pull the threads 90 from under the points of the needles so that the same can be readily cut, the operator rotates the shaft 29, and swings the arms 31 and the bars 33 carried thereby to the position shown in Fig. 5. In this movement of the bars, the threads are received in the notches 35 of the bars and moved upwardly. By the movement of the shaft 95 29, the weight 36 is swung upon the opposite side thereof so that said weight will hold the notched ends of the bars 33 in their elevated positions. The threads may thus be 100 readily cut. Owing to the fact that at the completion of the sewing operation, the wider ends of the blades 15 are between the 105 needles, considerable time would be consumed and difficulty experienced in picking out the threads and separately cutting the same so that the work could be removed. By providing the device above described, the 110 threads may be very easily and quickly cut and waste of the thread prevented while sufficient thread will remain in the point of the needles for the start of the next sewing operation. The weight 36 will at all times 115 hold the lower ends of the rods 33 out of contact with the needles while the machine 120 is in operation.

125 From the foregoing, it is believed that the construction and manner of operation 130

of my improved sewing machine will be clearly and fully understood. The invention provides simple and efficient mechanism for sewing diverging lines of stitching upon 5 glove-backs and admits of such work being quickly and accurately performed with comparatively little labor upon the part of the operator. The blades 15 may be easily and quickly removed and others substituted 10 therefor when it is desired to operate upon different kinds of material or to vary the degree of divergence between the rows of stitching. Owing to the comparatively simple construction of the invention, it will also 15 be obvious that the same can be produced at small manufacturing cost and is highly durable and efficient in operation.

While I have shown and described the preferred construction and arrangement of the 20 several elements, it will be understood that the invention is susceptible of considerable modification in the form, proportion and arrangement of the several parts without departing from the essential features or sacrificing any of the advantages thereof.

Having thus described the invention, what is claimed is:

1. In a sewing machine, a presser foot provided with spaced longitudinal slots, and 30 said slots and having longitudinally inclined spurred upper edges.

2. In a sewing machine, a presser foot provided with spaced longitudinal slots, spaced feeding blades slidably mounted for 35 movement through the slots in the presser foot, and a relatively stationary element to force the material downwardly between said blades.

3. In a sewing machine, a presser foot provided with spaced longitudinal slots, spaced feeding blades slidably mounted for 40 movement through the slots in the presser foot, and a pivotally mounted finger to force the material downwardly between said blades.

4. In a sewing machine, a presser foot provided with spaced longitudinal slots, spaced feeding blades slidably mounted for 45 movement through the slots in the presser foot, and a tapering finger pivotally mounted at one end to force the material downwardly between said blades.

5. In a sewing machine, a presser foot provided with spaced longitudinal slots, spaced feeding blades slidably mounted for 50 movement through the slots in the presser foot, a longitudinally extending tapering finger pivotally mounted at its wider end to 55 force the material downwardly between the blades, and a spring acting upon said finger

to yieldingly hold the same out of contact with the material.

6. In a sewing machine, a presser foot provided with spaced longitudinal slots, 65 spaced feeding blades slidably mounted for movement through the slots in the presser foot, a longitudinally extending tapering finger pivotally mounted at its wider end to force the material downwardly between 70 the blades, and means carried by the finger for engagement by the material whereby the same may be properly positioned beneath the presser foot.

7. In a sewing machine, a presser foot 75 provided with spaced longitudinal slots, spaced feeding blades slidably mounted for movement through the slots in the presser foot, a longitudinally extending tapering finger pivotally mounted at its wider end to 80 force the material downwardly between the blades, and a pin carried by said finger to limit its downward movement and for engagement by the material to properly position the same beneath the presser foot.

8. In a sewing machine, a presser foot provided with spaced longitudinal slots, 85 slidably mounted parallel blades having their upper edges longitudinally inclined and movable through the slots in the presser foot, said inclined edges of the blades being provided with spaced spurs for gripping engagement with the material.

9. In a sewing machine, parallel guide bars mounted upon the bed plate of the machine, cross heads arranged between said bars and longitudinally movable thereon, a presser foot disposed between the guide bars and provided with spaced slots, longitudinally tapering material feeding blades movable through said slots and having their 95 ends removably engaged upon said cross heads.

10. In a sewing machine, parallel guide bars mounted upon the bed plate of the machine, cross heads arranged between said bars and longitudinally slidably thereon, a presser foot operating between the guide bars and provided with spaced longitudinal slots, material feeding blades having 100 inclined upper edges movable through said slots in the presser foot, the ends of said blades being notched for removable engagement upon the cross heads, and stops at the opposite ends of the guide bars to limit the 110 sliding movement of the cross heads.

In testimony whereof I hereunto affix my signature in the presence of two witnesses.

JAMES H. HAGAN.
